UNITED STATES PATENT OFFICE.

GEORGE WELIKI, OF HAMILTON, ONTARIO, CANADA, ASSIGNOR OF ONE-HALF TO
MARIA KAMINSKA, OF HAMILTON, ONTARIO, CANADA.

AEROPLANE.

1,395,068.

Specification of Letters Patent. Patented Oct. 25, 1921.

Application filed July 31, 1920. Serial No. 400,388.

To all whom it may concern:

Be it known that I, GEORGE WELIKI, a citizen of Russia, residing at Hamilton, Ontario, Dominion of Canada, have invented 5 certain new and useful Improvements in Aeroplanes, of which the following is a specification.

This invention relates to improvements in aerial conveyances, and particularly to apparatus of this nature which will ascend and descend in substantially vertical planes.

It is the object of the invention to provide an aeroplane of this character which is of an extremely simple construction and which 15 is provided with a special steering and propeller controlling means under the direct control of the operator, and which is capable of locomotion in horizontal, and also substantially vertical directions.

With these ends in view the invention consists in the novel construction and adaptation of devices, as will be hereinafter more fully described and claimed.

In the accompanying drawings—

Figure 1 shows an aeroplane constructed according to the present invention in side view, and

Fig. 2 is a top plan view of the same, partly in section on line 2—2 of Fig. 1.

The frame 10 of the aeroplane carries the wing 11 and cross-braces 11' and 12' and a flooring 13. To the bottom 14 is secured in a frame 15 the customary starting and landing wheels 16, and to the flooring 13 a bracket 17 carrying the shaft 18 for the lifting propellers 19.

Upon the flooring 13 a seat 20 for the operator is arranged and in front of the same the steering wheel and shaft 21 and 22 respectively for steering the aeroplane by means of the tail 23 in the customary manner. Seat 20 and steering wheel and shaft 21 and 22 are located within a chassis 24, at the forward wall of which the motor is arranged within a casing 25 provided with an exhaust pipe 26. The shaft 27 of the motor extends from the front of the casing 25, and its forward end is supported in a bearing 28 upon a post 29 on the flooring 13. Intermediate its length the shaft 27 carries a coupling sleeve 30 slidably arranged on said shaft which in turn carries a bevel gear 31 rotating therewith. To the sleeve 30 a rod 32 is pivotally connected as at 33, the free

end of which is pivotally secured to an operating lever 34 near its upper handle 35 within easy reach of the operator on seat 20, the lower end of the lever 34 being pivotally secured to the flooring as at 36. The bevel gear 31 is in mesh with another bevel gear 37 on a vertical shaft 38 extending through the flooring 13 and carrying below said flooring a bevel gear 39 in mesh with a similar bevel gear 40 on the shaft 18 of the lifting propellers 19.

The shaft 18 carries at its ends bevel gears 54 in mesh with bevel gears 55 on the shafts 56 of the propellers 19. Bearings 57 and 58 are provided for carrying shaft 18 under the flooring 13.

In front of the bevel gear 31 another sleeve 40' is slidably arranged upon shaft 27 carrying a bevel gear 41 rotating with said shaft. With this sleeve the rear end of a rod 42 is pivotally secured as at 43, the front end of which is pivotally secured near the handle 44 of a lever 45 in easy reach of the operator, which lever is also pivoted as at 46 on the flooring 13.

A shaft 47 is arranged parallel to shaft 27 above the same and is supported in a bearing 48 on post 29. The rearward end of shaft 47 extends beyond the bearing and carries a bevel gear 49 adapted to be engaged by bevel gear 41 upon suitable operation of the lever 45. The shaft 47 carries at its front end beyond the frame 10 a driving propeller 50.

A gas bag 51 is provided underneath the wing 11 and is secured to the frame by means of a hanger 52 secured on a hook 53. This gas bag is intended as a life-saving device for the operator in case of accident.

The device operates as follows:

If the operator desires to ascend, he starts the motor and couples by means of the lever 34 and sleeve 30 the bevel gears 31 and 37 for the operation of the shaft for the lifting propellers 19. When the plane has reached a certain level, he operates lever 45 to shift sleeve 40' and bring bevel gear 41 into mesh with bevel gear 49 for the rotation of shaft 47 of the driving propeller 50, and at the same time operates bevel gears 31 and 37. The steering is effected 105 by the operation of the tail piece 23 by means of the steering wheel 21 and co-operating parts.

Having thus described my invention what I claim as new and desire to secure by Letters Patent of the United States is—

1. In a motor operated aeroplane of the character described, including a shaft for the motor, and lifting and driving propellers with their shafts, bevel gears on said shafts, and means for shifting the bevel gears on the motor shaft into and out of engagement with the bevel gears on the shafts for the lifting and driving propellers, 20 said means comprising coupling sleeves slidably arranged on the motor shaft, horizontal rods pivotally secured with one of their ends to said sleeves respectively, and hand levers near the operator's seat pivotally connected to the opposite ends of said horizontal rods substantially as described and for the purpose set forth.
2. In a motor operated aeroplane of the character described, including a shaft for the motor and lifting and driving propellers with their shafts, bevel gears on said

shafts, and means for shifting the bevel gears on the motor shaft into and out of engagement with the bevel gears on the shafts for the lifting and driving propellers, 20 said means comprising coupling sleeves slidably arranged on the motor shaft, horizontal rods pivotally secured with one of their ends to said sleeves respectively, and hand levers near the operator's seat pivotally connected to the opposite ends of said horizontal rods substantially as described and for the purpose set forth.

In testimony whereof I have affixed my signature.

GEORGE WELIKI.
